MACHINE FOR POSTING AND MANIFOLDING BUSINESS RECORDS

William Dale Winders, Columbus, Ohio

Application August 4, 1954, Serial No. 447,867

8 Claims. (Cl. 282—5)

This invention relates to record-manifolding machines, the same having particular reference to an improved machine for posting and manifolding bookkeeping records, such as those of commercial establishments selling goods on credit, or other organizations in which installment and various other periodic payments are made by purchasers, borrowers, or other customers.

Machines for facilitating and governing the making and entering of installment and other similar payments are disclosed in my prior Patents Nos. 2,656,198 and 2,656,199, granted October 20, 1953. The present invention aims primarily to simplify, render more compact, and improve generally the mechanical construction of such machines, and particularly the machines disclosed in said patents, through rendering the same more positive, reliable, and effective in their operation, smaller in overall dimensions, and less likely to produce error as a result of operator-performed mistakes or oversights in the mechanical actuation of the machines.

Another aim or object of the present invention is to provide a manifolding machine for the general uses and purposes set forth, and which is formed to embody a casing structure having a flat, record-receiving, top wall in which is provided an entry-posting slot, and wherein the interior of the casing structure is formed, in vertical registry with said slot, with a rotatably mounted, drum-type platen, the relative order of these parts being such as to enable the platen to support on its outer circumference, and in alignment with said slot, a plurality of separable entry-receiving sheets which are entirely confined within the machine casing, but which are adapted to have selected areas thereof aligned for manifolded posting with one or more record sheets disposed on the upper surface of the top wall of said casing structure, the platen serving to reduce the total length of the structure by avoiding longitudinal shifting of flatly maintained entry or ledger sheets placed within the machine, as heretofore required.

A further object is to provide a manifolding machine of the character indicated in which a record sheet may be inserted into a side-opening receiving pocket formed therefor in the outer casing construction of the machine, and wherein a rotatable platen is so arranged within said casing as to engage a sheet inserted into said pocket and, upon rotation of the platen, to advance various portions of the sheet into registry with an associated posting slot formed in the casing's top wall, whereby to provide a relatively short compact machine assembly.

Another object is to provide a posting or manifolding machine of this category wherein a spool-actuated, entry-receiving ribbon or tape may be employed as a lock-protected, unaltered journal or daily receipts record, and wherein the ribbon or tape is movable between mounting and receiving spools provided therefor within the casing, the same being so arranged that the length of the tape extending between said spools will pass over the uppermost part of the outer circumference of the movable platen roll rotatably mounted within the casing, the strip being

2

thus locally presented to a posting slot formed in the top wall of the casing, the arrangement providing for locked retention of the journal tape within the casing and the posting of entries thereon from the exterior of the machine.

A still further object of the invention is to provide the top wall of the outer casing of such a machine with a hingedly movable, sheet-clamping plate, the latter being operable to fixedly retain one or more separable record sheets in fixed positions on the upper surface of said top wall and with selected areas of the sheets in registry with an associated posting slot formed in said top wall, and wherein an improved manually released latch mechanism is provided for normally retaining the clamping plate in a lowered record-clamping position in which the plate is disposed in adjoining parallel relation with said top wall.

Other objects are: to provide manually operated means for imparting incremental rotation to the receiving spool of the casing-protected journal tape, said means being interrelated with the releasing latch mechanism of the aforesaid hinged record sheet clamping plate, so that in order to release said plate to permit it to be raised or otherwise moved to a position providing for the insertion of record sheets into or the removal of such sheets from clamping engagement with the plate, the construction and actuation of the manually operated means are such that the same will, first, partially rotate the tape-receiving spool to effect automatically movement of the journal tape in bringing fresh entry-receiving areas thereof into successive registry with the casing-formed posting slot, and, second, will release the clamping plate for record insertion; to provide in such a machine a clamping plate closed window in the top wall of its casing through which individually identified entry-receiving areas of a concealed machine-contained ledger sheet are externally viewable when the plate is raised, whereby to enable an operator, through rotation of an associated external platen roll control, to move or adjust a ledger sheet so that a given entry-receiving area thereon may be aligned with a cooperative posting slot of the machine; to provide in such a machine an improved clutch mechanism for imparting incremental rotation to the receiving spool of a journal ribbon or tape and wherein the construction of the clutch mechanism is such as to rotate the spool when an externally projecting, manually actuated control is rocked in one direction and to release the spool when the control rocks in a return or opposite direction; and to provide a machine which constitutes an improvement generally in machines of this classification.

For a further understanding of the present invention, reference may now be had to the following description and the accompanying drawings, wherein:

Fig. 1 is a perspective view of a manifolding machine formed in accordance with the present invention;

Fig. 2 is a vertical longitudinal sectional view taken through the machine on the line 2—2 of Fig. 1;

Fig. 3 is a vertical transverse sectional view taken on the plane disclosed by the line 3—3 of Fig. 2;

Fig. 4 is a similar view on the line 4—4 of Fig. 2;

Fig. 5 is a detail fragmentary longitudinal sectional view on the line 5—5 of Fig. 4;

Fig. 6 is a similar view taken on the plane indicated by the line 6—6 of Fig. 4;

Fig. 7 is a detail transverse sectional view on the line 7—7 of Fig. 6;

Fig. 8 is a similar view on the line 8—8 of Fig. 7;

Fig. 9 is a fragmentary vertical transverse sectional view on the line 9—9 of Fig. 2;

Fig. 10 is an enlarged detail longitudinal sectional view on the line 10—10 of Fig. 1;

Fig. 11 is a similar view of a modified form of the machine of the present invention;

Fig. 12 is a fragmentary plan view of a ledger card used in connection with my improved manifolding machine;

Fig. 13 is a fragmentary vertical transverse sectional view showing the cover plate in its elevated position suitable for the placement of a record sheet on the upper surface of the machine for the making of an entry thereon;

Fig. 14 is a detail perspective view of a receipt book useful in connection with the posting machine of the present invention;

Fig. 15 is a detail perspective view of a ledger sheet or card also adapted for use in connection with the machine of the present invention.

Referring more particularly to the drawings, I employ in my improved manifolding machine a casing structure comprising a stationary base B and a cover C. In this instance the cover C includes an open bottom formed by a pair of transversely spaced, vertically disposed, side walls 22, a front wall 23, a back wall 24, and a flat top wall 25, the latter, as shown, sloping forwardly and downwardly in an inclined plane between the back and front walls, 24 and 23, respectively. The lower edge of the back wall 24 is hinged, as at 21, to the rear edge of a stationary base plate 40, the front wall 23 being provided with a key-operated lock 41 which cooperates with a keeper 42 to retain the cover in its normally lowered position.

In the forward and lower part thereof, the wall 25 of the cover is formed with a rectangular depressed region 26. In this region there is provided an elongated, relatively narrow posting or writing slot 27. Also occupying the recess is a sheet-holding or clamping plate 28 which is formed with a slot 28a adapted to register with the slot 27 when the plate 28 is lowered. The latter is hinged, as at 29, along one of its longitudinal edges, the hinge including spring means 30 so arranged as to apply forces to the plate tending to move the same normally to an elevated position above the recessed region 26. To hold the plate against such spring bias in its lowered sheet-clamping position, as shown in Figs. 4 and 6, the edge of the plate opposite to and parallel with the hinged edge 29 thereof is formed with a rigid, depending keeper yoke 31 which extends through an opening 32 formed in the top wall 25, so that the yoke may receive the beveled end of a sliding latch member 33.

This latch member, as shown herein, is formed to be slidably received in a boxing 34 carried by the under side of the wall 25, a coil spring 35 being disposed in said boxing in a position in which one end of the spring bears on the latch member to force the latter rearwardly into latching contact with the yoke 31. The latch member includes a rigid, depending, angularly formed operating stem 36 which projects through a slot provided in the bottom of the boxing and has an out-turned end disposed between a pair of spaced lugs 37 projecting from the periphery of a disk 38 carried by a spool shaft 39 which extends transversely of the casing 30 and interiorly thereof.

Through the provision of manually actuated means, hereinafter more fully defined, rocking movement is adapted to be imparted to the disk 38 to bring one of the lugs 37 thereof into engagement with the stem 36, thereby controlling the retraction of the latch member against the force of the spring 35 in releasing the clamping plate and allowing the same to swing upwardly under the influence of the spring hinge 29. This spring-induced raising of the plate permits one or more record or receipt sheets R, as shown in Fig. 10, to be inserted into the recessed or depressed region of the wall 25 of the casing. The sheets may be securely held in said region with selected portions of the sheet or sheets in registry with the writing slots 27 and 28a after the plate is lowered and latched.

Stationarily carried by the base plate 40 and forming a part of the base B is a channel member 43 which embodies a horizontal bottom web 44 and upstanding side flanges 45 disposed within the confines of the cover mem-

ber C when the latter is closed and in adjacent parallel relation with the side walls 22 thereof, as shown in Figs. 3 and 4. Connected with the upper portions of the flanges 45 is a table plate 46 which, when the cover member is closed, extends immediately below and in parallel relationship with the top wall 25 of the cover member. The plate 46 is formed with a slot 47 arranged in vertical registry with the posting slot 27.

Toward their rear ends the side flanges 45 are formed with bearing openings for the reception of a removable mounting or supply spool 48. On this spool there is wound a paper tape or strip 49, the spool containing the tape being inserted upon or removed from the flanges 45 when the cover member C occupies its raised position. With the cover member so raised, the free end of the tape or strip is trained over the upper surface of the table plate 46, so that when the cover member is subsequently lowered and locked in its closed position, an elongated web-forming length of the tape, indicated at w, will be disposed between the table plate 46 and the top wall 25 of the cover member. This web will register with the slots 27, 28a, and 47, so that through carbon impression-transferring means contained on a receipt sheet or sheets R, held by the clamping plate 28 on the upper surface of the top wall 25, one writing an entry or other record on a top sheet R will cause the simultaneous posting of the same entry or record on the tape or strip 49.

The web w of the tape 49, at the region thereof in registry with the aligned writing slots 27, 28a, and 47, is supported by a cylindrical drum-shaped platen 50. As shown in Figs. 2 and 3, the platen is mounted on and rotatable with a shaft 51 which is journaled for rotation in aligned openings 52 formed in the side flanges 45 of the channel member 43. There is mounted on the channel member 43 in spaced, parallel relation to one of its side flanges 45 a vertical wall 54, the latter defining the inner or closed side of a pocket 55 employed for receiving ledger sheets 56 adapted for use in connection with the machine. The shaft 51 at one end thereof includes an exteriorly disposed hand knob 57, and one of the side walls 22 of the cover 20 is slotted, as at 58, for the reception of the hub of the knob 57. Preferably the outer periphery of the platen 50 is raised, as at 58', where the platen is in registry with the slots 27, 28a, and 47, so that the raised portion will project into the slot 47 of the table plate 46 to bring the record sheets to be manifolded into close order with each other. Internally, the drum-type platen 50 is provided with end-positioned spiders 59 formed with hubs for the reception of the shaft 51.

The pocket 55, in addition to its closed side wall 54, is further provided with and defined by a sloping bottom wall 60, a vertical rear wall 61 disposed adjacent to and in parallel order with the tape-mounting roll or spool 48, and an open side, as shown at 61a, the latter being formed, as shown in Fig. 9, by registering slots formed in one of the side walls 22 of the cover member 20 and one of the side flanges 45 of the channel member 43. A longitudinally extending, laterally adjustable guide flange 62 is arranged at the closed side of the pocket to limit insertive movement of the ledger sheets 56 when the latter are introduced into the pocket 55 through the open side thereof. The flange 62 forms in effect an adjustable continuation of the fixed pocket wall 54. Clamping screws 63 may be employed in retaining the adjustment of the guide flange 62, the shanks of the screws being slidably arranged in slots 64 formed in the bottom wall 60 of the pocket.

Ledger sheets introduced, with the upper faces thereof disposed downwardly, into the machine through the open side of the pocket are deposited flatly on the bottom wall 60, the same being advanced by finger pressure or gravity in engagement with the bottom portions of the platen 50 and into contact with rollers 65 mounted at intervals in an arcuate front wall 66 of the pocket 55. As shown in Fig. 10, the upper end of the front wall 66 terminates, 75 in this particular construction, in a flat extension 67

which is disposed immediately beneath and in parallel relation with the table plate 46 of the machine base, the extension being slotted, as at 68, to permit the upper part of the platen to project therethrough. Beyond the flattened and slotted portion thereof, the extension terminates in an arcuate lip 69 extending in part around the platen and equipped with one of the rollers 65.

Thus, when one of the sheets 56 is inserted into the pocket 55 and brought into edge engagement with the lower part of the platen, normal rotation of the latter will cause the inserted sheet to follow the platen and to move in unison with the latter by passage through the arcuate slot formed between the outer circumferential wall of the platen and the arcuate forwardly disposed wall 66 of said pocket. The ledger sheets so positioned will be advanced by the platen until desired regions or selected entry-receiving areas on the ledger sheets will be presented in a position of registry with writing slots 27, 28a, and 47 and in close contact with the receipt or record sheets R placed on the top of the machine beneath the clamping plate 28, and also in close engagement with the tape or strip 49 which is movably supported under lock and key retention within the casing structure of the machine.

In advancing the strip or tape 49 longitudinally by incremental progression for each posting operation, so that a fresh unused portion of the tape will be brought into registry with the posting slots for the making of manifolded entries, the forward end of the web w of the tape is directed downwardly over a guide lip 70 (see Fig. 2) formed on the forward end of the table plate 46. This free end of the tape is suitably united with a winding or receiving spool 71 rotatably supported on the front end of the machine base. In this instance the body of the spool 71 is fixed on the shaft 39 which has its opposite ends journaled in openings formed in bracket plates 73 secured to the inner faces of the side flanges 45 of the channel members 43 of the machine base.

In order to apply step-by-step rotation to the spool 71, means are provided to move fresh portions of the tape 49, which preferably is in the form of a journal or daily receipts record, into registry with the posting slots, and to coordinate the movement of the tape with the actuation of the clamping plate 28, so that the operator of the machine will not be permitted to overlook moving the tape for the making of each entry. Toward this end, the disk 38 on which the latch-operating lugs 37 are formed is provided, as shown in Figs. 6 and 7, with a radial slot 74 formed to provide a rounded inner end and an outwardly diverging portion which extends to the periphery of the disk 38. Positioned in the rounded inner end of the slot 74 is the cylindrical bearing portion of a crank pin 75. Carried by and projecting outwardly and radially from the pin 75 through the flaring outer portion of the slot 74 is a crank arm 76. Pivoted, as at 77, to a head formed on the outer end of the arm 76 is one end of a link 77', the opposite end of said link being pivotally joined, as at 78, with the weighted end 79 of an oscillatory manually actuated lever 80.

The hub 81 of this lever is mounted for free turning movement on the shaft 39 at one end of the latter, and the control lever 80 includes a forwardly projecting end which, as shown in Fig. 6, extends for oscillatory movement through a vertical slot 82 formed in the front wall of the cover C, the movement of the lever 80 being indicated by full and broken lines in Fig. 6.

To produce longitudinal movement of the journal strip or tape 49 during substantially the full downstroke of the lever 80 and prior to unlatching of the clamping plate, the crank pin 75 is formed with a semicylindrical end 83 which is adapted to be positioned between adjacent faces of a pair of semicircular clutch elements 84 and 84', the element 84' having a recess therein in which the semicircular outer surface of the end 83 of the crank pin is rockably positioned. It will be seen

that when the lever 80 is manually depressed, the resulting upward movement of the weighted end 79 thereof through the linkage 77 joined therewith causes rocking movement on the part of the crank pin 75 about its longitudinal axis.

This movement of the pin causes the semicylindrical flattened end thereof to so engage the adjacent faces of the clutch elements 84 as to produce when turned separation or outward expansion of said elements, so that the arcuate outer faces of the clutch elements frictionally grip the circular peripheral wall surfaces of a chamber 85 in which the clutch elements are positioned. The chamber 85 is formed in one end of the front spool 71 in order that the oscillatory motion of the downwardly moving lever 80 will, upon initial movement thereof, be transmitted to the clutch elements and thence to the tape spool, thus pulling the tape forwardly a desired linear distance. Toward the end of this forward movement one of the lugs 37 of the disk 38 contacts the stem 36 of the latch mechanism to effect the unlatching of the clamping plate 28 and its elevation to a record-receiving position. Upon normal release of the lever 80 when the outer end thereof reaches its lowest position in the slot 82, the weighted end 79 of the lever serves to restore the latter to its normal position, as shown in full lines in Fig. 6. This construction is strong, positive, and durable and avoids the use of springs and other relatively fragile parts which are apt to break or become out of working order.

To hold the front spool 71 positively in its positions of adjustment between increments of arcuate movement thereof, the spool shaft 39, as shown in Fig. 5, carries at one end a disk 86 having arcuate recesses 87 formed in its outer circumference. Adapted to enter and slot in these recesses is a roller 88 mounted on an upper link member 89. One end of this link member is pivotally connected, as at 90, to a stationary supporting member 91 carried by a base element of the machine. Pivotally connected to the lower end of the member 91 is the rear end of a movable arm 92 which extends forwardly beneath the under portion of the disk 86. The outer ends of the arm 92 and the link member 89 are united by a coil spring 93 which serves to maintain the roller 88 in a seated position in any one of the recesses 87 to hold the front spool against rotation unless positively actuated by the lever 80. At its front end the arm 92 terminates in a projecting finger 92a, shouldered at 92b for engagement with a lug 92c carried by and extending inwardly from the front wall of the cover or lid C. When the latter is closed, as in Fig. 5, the bracket or lug 92c presses downwardly on the finger 92a in a manner holding the detent roller 88 in the notches of the wheel 86, the spring 93 being placed under tension.

One of the important features of the present invention resides in providing the recessed region of the top wall of the cover C with a window opening 95. This opening is normally concealed or covered by the hinged clamping plate 28, as shown in Fig. 1. The ledger sheets 56 are each formed with ruled parallel lines providing between them, as shown in Fig. 15, individually identified entry-receiving spaces 96, as by the use of consecutive numbers. When the ledger sheet is placed in the pocket 55 of the machine, with the ruled face thereof disposed downwardly, the subsequent rotation of the platen 50 will bring the inserted ledger sheet upwardly around the platen and into alignment with the casing-formed posting slots. In aligning a particular space on the ledger sheet with the posting slots, the machine operator notes the number identifying the space in which a given posting is to be entered. When the identifying number, or other insignia, of this selected space is viewed through the window opening 95, the operator will be informed as to the accuracy of the alignment. It will be noted that to make such a viewing and determination, the clamping plate must be elevated, and to effect such elevation it is first necessary

for the operator to actuate the lever 80, thus moving the journal tape 49 to present a fresh unused area thereof to the posting slots. These features of interaction between the clamping plate release and the tape-spooling control require correct operation automatically on the part of the various elements of the machine, so that error or mistake in its operation is virtually automatically precluded.

In the use of my improved machine, as it is employed in crediting customers' installment or other periodic payments, the control lever 80 is first depressed in order that it may be rocked from the full line position of Fig. 6 to the broken line position. This movement of the lever, through the immediate expansion of the clutch elements 84 and 84', produces turning movement of the front spool 71 throughout substantially the full downward movement of the outwardly projecting front end of the lever and at the same time lifts the weighted rear extension 79 thereof. Thus, following depression of the front end of the lever and customary release thereof, the lever will return automatically to its original or normal position, as shown by full lines in Fig. 6, by the gravitational response of its weighted end 79. During depression of the lever, the journal strip has its intermediate length moved linearly as a result of the lever and clutch-effected rotation of the front spool 71, whereby to present a fresh unused area thereof to the aligned posting slots. During return movement of the lever from its depressed position to its elevated normal position, the clutch releases and the spring-pressed retaining means 87 and 88 operate to hold the front spool against rotation.

After the front spool has been thus rotated to bring an unused region of the tape 49 into registry with the posting slots, the latch mechanism 33 is operated when the outer end of the lever 80 reaches approximately the lower limit of its travel. At this time one of the lugs 37 on the disk 38 contacts the latch stem 36 to withdraw the latch from holding engagement with the keeper yoke of the clamping plate 28 so that the latter may be moved upwardly to a record-receiving position by the action of its spring-biased hinge mounting 29.

With the clamping plate so elevated, a ledger sheet 56, containing a given customer's account, is positioned with the face thereof disposed downwardly on the sloping bottom wall 60 of the pocket 55. The platen 50 is then rotated to bring the proper entry-receiving line or space 96 of the sheet 56 in which an entry is to be posted into registry with the vertically aligned posting slots formed in the upper casing walls. This alignment may be determined accurately from the exterior of the machine by viewing the identifying number, or other insignia, appearing in connection with the selected line or space through said window opening.

The customer's receipt sheet R is then placed in the recessed or depressed region 26 of the top wall 25, with the line or lines thereon in which an original entry is to be made disposed over the posting slots. Thereafter, the plate 28 is lowered and latched, thereby retaining the record sheet, or sheets if more than one is employed, against casual displacement and in fixed relative order. It will be noted that the edges of the writing or posting slot formed in the plate 28 are inwardly and downwardly curved in a manner causing the plate when closed to engage and force the sheet or sheets R into the posting slot to bring the same into close engagement with the underlying tape and ledger sheets and the upper surface of the platen 50. If desired, the upper edge portion of the clamping plate may carry a removable guide strip 98 showing the particular headings or columns of the entry-receiving sheet or sheets in which postings are to be made.

In producing manifold copies of entries hand written on the record sheet R, it will be appreciated that the back of such a sheet may be provided with spotted carbon areas so that the entries made on the customer's record sheet may be transferred to the underlying journal tape or strip 49. Also, the lower or back surface of this tape

or strip may likewise be provided with carbon areas for the automatic transference of the record sheet and tape entries or postings to the ledger sheets 56. While separate carbon sheets or strips may be used in effecting such manifolding of entries made on the top record sheet to sub-placed record sheets, the so-called "spot" carbon method of transference is employed in the interest of simplicity.

The rotatable platen is advantageous in a machine of this type in reducing its total length. In the machines disclosed in my prior patents, considerable length was required in order to permit a flatly inserted ledger sheet to be adjusted in a horizontal plane longitudinally of the machine in aligning a selected entry-receiving space on the sheet with the posting slots or openings. The rotatable platen herein disclosed enables the sheets 56 to be curved about the outer cylindrical wall of the platen, so that a substantial shortening of the total length of the machine is made feasible. Again, with the use of the rotatable platen, the ledger sheets when operatively arranged within the machine are entirely concealed from view. Thus, in order to ascertain alignment of a given region thereon with the posting slots, it is necessary to operate the control lever 80 to move the tape or strip 49 before the clamping plate 28 can be raised to permit the line-identifying numbers on the ledger sheets to be viewed through the window opening 95. The tape or strip is maintained under lock and key retention within the machine, and at the end of a day or other period, the tape or strip may be removed by one in authority and the day's cash receipts reckoned therefrom. The machine thus provides a cashier with a simple and convenient means for posting simultaneously a given entry on a plurality of different record sheets. By so manifolding such an entry, the customer, cashier, and management are provided with accurate duplicative records, so that errors and misunderstandings are avoided. As a result of the lock-controlled journal tape, misappropriation of receipts is minimized through the relative ease by which ready detection thereof is made possible.

After an entry inscription has been made on a ledger sheet 56, the platen may be further rotated in the same direction it was rotated in presenting the ledger sheet to the inscription slot in order that the sheet may be 45 redelivered to the pocket 55 for removal from the machine, as shown in Fig. 10. An alternative construction has been illustrated in Fig. 11, wherein a blind recess 99 is formed in the base frame of the machine which receives the ledger sheet during entry inscription, but which requires that the direction of rotation of the platen be reversed when the inscribed ledger sheet is to be returned to the pocket 55. In this form of my invention the table plate 46 is extended to provide a stationary shelf extension 100 which acts as a support or platen, so that the 50 drum 50 merely serves as a ledger sheet-advancing and retracting means.

Other variations or modifications are, of course, contemplated within the scope of the following claims.

I claim:

1. In a manifolding register; an elongated box-like casing having a top wall formed with an intermediately disposed transversely extending entry-writing slot; a clamping plate mounted on said top wall for movement between a lowered record sheet-clamping position and a relatively elevated position of sheet release; means within said casing for supporting and guiding a concealed record sheet in the form of an elongated web beneath said top wall and the slot therein; means for drawing said web past said slot embodying a rotatable member mounted in one end of said casing and to which one end of the web is fastened to effect winding thereof upon said member as the latter is rotated; manually operated means for imparting incremental rotation to said member, including a shaft; an exteriorly accessible operating lever mounted 65 for oscillatory movement on said shaft; means biasing 70 in one end of said casing and to which one end of the web is fastened to effect winding thereof upon said member as the latter is rotated; manually operated means for imparting incremental rotation to said member, including a shaft; an exteriorly accessible operating lever mounted 75 for oscillatory movement on said shaft; means biasing

said lever to return the same to an initial position following manual actuation and release thereof; single-acting clutch means operative upon manual actuation of said lever to impart turning movement to said rotatable member and to release said member upon return movement of the lever to its initial position; latch means disposed within said casing and normally retaining said plate in its sheet-clamping position; spring means tending to move said plate to an elevated sheet-releasing position; and trip means operative only following predetermined web-advancing movement of said rotatable member for actuating said latch means in the release of said plate.

2. In a manifolding register; an elongated box-like casing having bottom, side, end and top walls defining an internal compartment, the top wall intermediately of its length being formed with a transversely extending posting slot, said wall supporting thereon an upper record sheet in adjustable registry with said slot, one of said side walls being formed with a longitudinally extending opening; a manually operated platen drum rotatably mounted in said casing compartment adjacent the slot in said top wall; supply and winding rolls rotatably mounted in longitudinally spaced order in said compartment, said rolls receiving the end portion of an intermediate record sheet in the form of an elongated web; guide means arranged in said casing for advancing an intermediate length of said web beneath said top wall and between the upper part of said platen drum and said slot; manually operated means for imparting intermittent movement to said web in withdrawing the same from the supply roll and winding it upon the winding roll; and guide devices positioned in said compartment forming a pocket accessible through the opening in the side wall of the casing, said devices including a forwardly inclined bottom structure that terminates beneath said drum in an upwardly and arcuately formed portion disposed in sheet-guiding concentric relationship with the adjacent forward portion of said drum, said devices serving to direct a forward edge of a bottom or third record-receiving sheet deposited in said pocket on the inclined bottom structure thereof into engagement with the lower portion of the drum, so that upon rotation of the drum in a predetermined direction the sheet engaged thereby will be caused by the arcuate portion of said guide devices to be flexed about said drum and brought into entry-receiving registry with said slot.

3. Manifolding register mechanism as defined in claim 2, and wherein the top wall of said casing adjacent one end of the slot therein is formed with window means to enable an operator to visually ascertain the particular part of the casing-enclosed third record sheet in registry with said slot; a clamping plate hingedly mounted on said top plate for maintaining an upper record sheet in a fixed position of registry with said slot, said plate when in its sheet-clamping position being extended to conceal said window means from external view.

4. Manifolding register mechanism as defined in claim 2, and wherein the top wall of said casing adjacent one end of the slot therein is formed with window means to enable an operator to visually ascertain the particular part of the casing-enclosed third record sheet in registry with said slot; a clamping plate hingedly mounted on said top plate for maintaining an upper record sheet in a fixed position of registry with said slot, said plate when in its sheet-clamping position being extended to conceal said window means from external view; latch means

carried by and arranged within said casing for retaining said plate in its clamping position against a spring bias; manually operated means for imparting incremental turning movement to said web-winding roll; and trip means operable following predetermined movement of said web for operating said latch means to release said plate.

5. Manifolding register means as defined in claim 2, and wherein blind pocket-forming means are provided in conjunction with and immediately beneath said top wall for the support of rearwardly extending portions of a third or bottom record sheet held by said drum in registry with the top wall slot and which project beyond the upper circumferential portion of the drum.

10 6. Manifolding register means as defined in claim 2, and wherein the arcuate portions of said guide device are provided with pressure rolls having sheet-confining contact with adjacent peripheral portions of the drum.

7. In an entry-manifolding register; an elongated box-like casing having a flat, substantially horizontally disposed top wall, the latter being formed intermediately of its length with a transverse inscription slot; a record-clamping plate carried by said top wall for movement between a substantially horizontal position of clamping engagement with a record sheet removably placed on

20 said top wall over said slot and a relatively elevated position of sheet release; biasing means serving to move said clamping plate automatically from a latched sheet-clamping position to its elevated position of sheet release; latch means disposed within said casing and normally holding said plate in its sheet-clamping position against the action of the biasing means; means arranged within said casing for directing a second record sheet in the form of an elongated web along the under part of said top wall into entry-receiving registration with said slot,

25 said last-named means including longitudinally aligned, relatively spaced, supply and winding spools for the web; manually operated means independent of said plate operable to impart incremental rotation to said winding spool in advancing said web beneath the slot in said top wall;

30 40 and means operable only following the impartation of predetermined movement to said web by said manually operated means for withdrawing automatically said latch means from its position of holding engagement with said clamping plate.

45 8. In a manifolding register; a casing having a top wall formed with a slot; a winding spool for the reception of an entry-receiving web rotatably mounted within said casing beneath said top wall and the slot therein; manually operated means for imparting successive increments of

50 rotational movement to said spool; a record sheet clamping plate hinged to said top wall on the upper surface thereof for movement between an active sheet clamping position of parallel engagement with said top wall and an elevated position of sheet release; releasable latch

55 means disposed within said casing and normally holding said plate against movement when in its sheet-clamping position; and means connected with said manually operated means and engageable with said latch means only following incremental rotational movement of said spool for releasing said latch means.
